UNITED STATES PATENT OFFICE.

JOHN TREGONING, OF NEW YORK, AND HIRAM S. MAXIM, OF BROOKLYN,
ASSIGNORS TO THE UNITED STATES ELECTRIC LIGHTING COMPANY, OF
NEW YORK, N. Y.

CARBON-HOLDER FOR ELECTRIC LAMPS.

SPECIFICATION forming part of Letters Patent No. 244,501, dated July 19, 1881.

Application filed February 19, 1881. (No model.)

To all whom it may concern:

Be it known that we, JOHN TREGONING, of the city, county, and State of New York, and HIRAM S. MAXIM, of the city of Brooklyn, county 5 of Kings, and State of New York, have invented certain new and useful Improvements in Devices for Attaching Carbons to a Lamp or Regulator; and we do hereby declare the following to be a full, clear, and exact description of the invention, reference being had to accompanying drawings, which form a part of this specification.

Our invention consists in devices for attaching the carbon-electrodes to the rack-bar or 15 sliding rod of the feed mechanism of an electric lamp, and is explained by reference to the drawings, in which—

Figure 1 is a central sectional view of the holder and its flexible connecting wire or rod; 20 Fig. 2, the same in elevation; Fig. 3, a perspective of the upper, and Fig. 4 of the lower, portions of the holder.

We have found that the ball-and-socket joint commonly used for attaching the carbon-holder 25 to the rack-bar or other part of the lamps becomes easily oxidized; and, furthermore, that it is necessary to employ some kind of clamping device—such as a set-screw—for fixing the holder in the position to which it may have 30 been adjusted. To overcome these objections we construct our holder by casting it or otherwise from some good conducting metal, and in two separate parts, A and B, and attach them to a flexible conducting rod or wire, C, 35 passing through their hollow centers. Each part A B has a slot along a part of its length, extending inward as far as the center to form clamping-jaws, which are drawn together by screws E D, passing through holes e d in the 40 slotted portion, as shown. By tightening these screws the two parts of the holder are clamped securely to the connecting-wire C. The lower part, A, is provided with a socket or cup, to which the end of a carbon pencil is fitted and 45 secured. The upper part, B, is internally screw-

threaded through a portion of its length, and is adapted to screw on the end of the rack-bar of the lamp. The wire C may extend up into the holder or rack-bar, so that it may be drawn down and utilized in case that portion which 50 is subjected to continual bending should break off.

To prevent twisting or breaking the wires between the two parts of the holder, we cut out from one part, as B, a recess, G, into which fits 55 a corresponding projection, F, on part A. The two portions of the holder should be secured not more than one-quarter of an inch apart, as this allows of all ordinary adjustments.

In the foregoing we have described the holder 60 as suitable for use only with the rack-bar or clamp-rod of the ordinary regulator-lamps; but it is obvious that without departing from our invention this holder, with its capabilities of adjustment and perfect conductivity, may be 65 employed for either the upper or lower carbon, or used generally to attach the pencils to any part of the lamp desired.

Without confining ourselves to the exact form or construction of the device as shown, 70

What we claim as our invention is—

1. A socket or holder for carbon-electrodes, constructed in two parts, clamped to a flexible connecting rod or wire, one part containing a 75 socket for the end of the carbon and the other having suitable means of attachment to the lamp, substantially as shown and described.

2. A socket or holder for carbon-electrodes, constructed in two parts, clamped to a flexible connecting rod or wire, one part having a projection fitting loosely in a recess in the other to prevent the twisting of the wire, substantially as shown.

In testimony whereof we hereunto set our hands this 18th day of February, 1881.

JOHN TREGONING.
HIRAM S. MAXIM.
